UNITED STATES PATENT OFFICE.

JOHN S. BURDICK, OF STRATFORD, CONNECTICUT.

LOCK.

Application filed July 9, 1919. Serial No. 309,583.

To all whom it may concern:

Be it known that I, JOHN S. BURDICK, a citizen of the United States, and resident of Stratford, county of Fairfield, and State of Connecticut, have invented certain new and useful Improvements in Locks, of which the following is a specification.

My invention relates to locks and more particularly to locks for doors of automobiles and other vehicles and has for its object to provide a simple construction whereby rattling of the closed door, due to the vibration of the vehicle, in motion, is efficiently prevented and whereby unintentional opening of said door is positively prevented. A further object of my invention is to provide a construction in which wear is automatically taken up and in which the bolt of the lock is capable of movement relatively to the striker plate in vertical directions whereby the lock is protected against strains resulting from the vibrations or movements of the body relatively to the door when the vehicle is in motion or when the body is under a load. Other more specific objects of my invention will appear from the description hereinafter and the features of novelty will be pointed out in the appended claim.

In the accompanying drawings, which, for illustrative and descriptive purposes show embodiments of my invention, Figure 1 is a horizontal section showing the lock applied to an automobile door; Fig. 2 is an elevation thereof; Fig. 3 is a perspective view of the striker plate and Fig. 4 is a view similar to Fig. 1 showing a different form of the lock.

The lock comprises a lock plate 5 upon the one face of which a slide 6 is mounted to reciprocate said slide being guided in a guideway 7 and being maintained in and returned to its operative position by means of a suitable spring 8 also mounted upon said face of the plate 5. The slide 6 may be manually moved against the tension of the spring 8 by means of members 9 rigidly carried by a short shaft 10 rotatably mounted in the plate 5 and projecting beyond the same as shown in Fig. 1. To facilitate the manual operation of the slide and the rotation of the shaft 10, the latter may be squared at its free end to receive any suitable and well-known type of handle secured in position in the customary manner. As so far described, the lock may be of any

existing and well-known construction other than the common arrangement shown, the novelty of the present invention residing entirely in the bolt and in the striker plate 60 which co-operates therewith to lock the door.

The bolt 11 is carried by the slide 6 so as to partake of the reciprocating movements thereof and normally projects beyond the flange 5^a of the lock plate 5, as shown in 65 the drawings. The bolt 11 is preferably of rectangular cross-section and is wedge-shaped or tapered at its outer end as indicated at 12, the taper 12 being preferably rounded at its free end, as shown in Figs. 70 1 and 4. In the form shown in Figs. 1 and 2 the bolt 11 is recessed at 13 to receive a roller 14 rotatably mounted upon a screwpin 15, the diameter of the roller 14 and its location in the recess 13 being such, that it projects peripherally beyond the bolt as illustrated in Fig. 1.

The bolt 11 co-operates with a striker-plate 16 provided with oppositely extending lugs 17 and with an outer inclined surface 18 leading to a continuing, relatively depressed inclined surface 19. The latter terminates at the bolt-recess 20 which tapers inwardly at angles corresponding to those of the tapering portion 12 of said bolt 11 and is of somewhat greater vertical dimensions than the bolt itself as illustrated in Fig. 2. At intermediate portions the upright converging walls of the bolt-recess 20 are formed with depressions 21 for the accommodation 80 of the roller 14 when the bolt 11 is in position in the bolt-recess 20; the depressions 21 are somewhat wider than the axial width of the roller 14 for the purpose to be more fully brought out hereinafter. In the form 85 shown in Fig. 4, the roller 14 and the depressions 21 are omitted, the construction being otherwise the same as the one shown in Figs. 1 and 2.

It will be noted that the parts are so arranged and proportioned that the bolt 12 has an outward range of movement in excess of that required to seat it in said recess and sufficient to permit said bolt to assume its operative position in the bolt-recess 20 under 100 the action of the spring 8. In other words when the door is closed this outward movement is arrested by the walls of the recess 20 so that the bolt 12 is firmly pressed into said recess by said spring 8 at all times regardless of any physical changes due to wear 105 and tear in either the recess or the bolt. 110

When the door is open the outward movement of the bolt 12 is stopped by the slide 6.

In practice, the lock is secured in proper position, for instance upon the door 22, of an automobile by means of screws 23 which pass through suitable openings in the lock plate 5 and the striker-plate 16 is fastened in proper co-operative relation upon the door-pillar 24 by means of screws 25 which pass through apertures in the lugs 17; the door 22 and the door-pillar 24 are suitably recessed for the accommodation respectively of the lock and striker-plate.

When the door is closed the tapered portion 12 of the bolt 11 is firmly seated in the bolt recess 20 of the striker-plate 16 and by reason of the fact that the bolt portion 12 fits the recess 20 snugly and is firmly pressed into the same by the spring 8 because of the frictional engagement between the side walls of said recess and the vertical sides of the bolt-portion 12, the door 22 is thus securely held against rattling due, for instance, to the vibration of the vehicle when in motion. At the same time, because of the fact that the vertical dimensions of the bolt-recess 20 are greater than those of the bolt 11 the latter is free to move in directions transverse to its taper in said recess 20 or more specifically is free to move vertically therein as the body and door of the vehicle move relatively to each other in such transverse or vertical directions from any cause. Such relative movements, due to the flexibility of the automobile construction, occur, for instance, when the vehicle is in motion and when it is under load. With the described arrangement, the transverse or vertical freedom of movement of the bolt 11 in the bolt-recess eliminates strains incident to such relative movement of the body and door from the bolt and other parts of the lock. This is very essential, particularly in automobiles in which the doors are oftentimes subjected to severe shocks and strains which would be transmitted not only to the lock itself and the devices whereby it is fastened to the door, but to the adjacent parts of the door construction, including the door hinges and the fastening means whereby said hinges are secured to the body, if the bolt were fixed against any transverse or vertical movement in the bolt-recess. The roller 14 interposes no interference to the relative transverse or vertical movements of the bolt and striker-plate, because the depressions 21 are of greater width than the axial width of said roller.

As the parts become worn from continued use, the wedge-shaped end 12 of the bolt 11 will enter further and further into the bolt-recess 20 under the action of the spring 8 and will therefore at all times snugly fit said recess and thus provide an efficient anti-rattling lock throughout its entire life.

The roller 14 by riding along the surfaces 18 and 19 as the door is opened and closed reduces the friction, incident to the engagement between the bolt and striker-plate to a minimum and thus increases the life of the lock. This roller 14, or in its absence as in Fig. 4, the free end of the bolt 11, in its travel across the striker plate is temporarily seated in the pocket formed at the junction of the striker-plate surfaces 18 and 19 and thus may hold the door against swinging open, if the force exerted to close it is not sufficient to bring said door to its fully closed position.

My invention is extremely simple in construction and efficient in operation and provides an arrangement in which the bolt and striking plate in themselves, and without the aid of any auxiliary door bumpers effectively prevent rattling of the door caused by a looseness between the lock bolt and striking plate, said arrangement at the same time insuring positive safety by preventing unintentional opening of the door. With my improvement the operation of opening and closing the door requires only a gentle force exerted either as a pull or a push; at the same time, wear of the parts is automatically taken up so that the bolt fits into the bolt-recess snugly at all times.

Various changes in the specific forms shown and described may be made within the scope of the claim without departing from the spirit of my invention.

I claim:

The combination of a striker-plate having a wedge-shaped recess and intermediate opposed depressions therein, a lock including a bolt having a wedge-shaped outer end fitting said recess and a roller carried by said bolt and arranged to ride along said striker-plate into said depressions, the vertical dimensions of the recess being greater than the vertical dimensions of the bolt and the vertical width of the depressions being greater than the axial width of said roller whereby said bolt and roller are vertically movable relatively to said striker-plate.

In testimony whereof I have hereunto set my hand.

JOHN S. BURDICK.
